CONTAINER FILLING MACHINE

Original Filed Oct. 23, 1928

UNITED STATES PATENT OFFICE

ROBERT N. CUNDALL, OF BLASDELL, NEW YORK, ASSIGNOR TO THE HOEPNER AUTOMATIC MACHINERY CORPORATION, OF BUFFALO, NEW YORK, A CORPORATION OF NEW YORK

CONTAINER FILLING MACHINE

Original application filed October 23, 1928, Serial No. 314,469. Divided and this application filed July 23, 1931. Serial No. 552,572.

This invention relates to a machine for filling containers with powdered materials such as talc, baking powder, and medical and toilet preparations of powdered form.

5 It is the object of this invention to provide improved means for accurately measuring the powdered material which is delivered to each of the containers.

This is a division of an application filed 10 October 23, 1928, Serial Number 314,469.

In the accompanying drawing:

Fig. 1 is a fragmentary vertical transverse section of a container filling machine embodying my improvements.

15 Fig. 2 is a similar view of the measuring device with the parts in a position different from that shown in Fig. 1.

Figs. 3 and 4 are fragmentary horizontal sections taken on the correspondingly numbered lines in Fig. 2.

Fig. 5 is a vertical section taken on line 5—5, Fig. 4.

Fig. 6 is a vertical section showing a modified form of the means for controlling the 20 discharge of powdered material from the supply reservoir.

In the following description similar characters of reference indicate like parts in the several figures of the drawing.

25 The stationary main frame of the machine upon which the working parts are mounted may be of any suitable construction but the same, as shown in the drawings, preferably comprises a pedestal 16, and a base 17 mounted on this pedestal and provided with forwardly projecting front brackets 18 and upwardly projecting rear brackets 19.

The numeral 20 represents the containers which are to be filled with the present machine and which may be of any suitable form in horizontal section and adapted to be closed at the upper end by a cap. These containers are moved past the filling position while mounted on the upper horizontal stretch of a 30 conveyor or feeding belt 22 and running over tracks 27 and the containers are held against lateral displacement from the feeding belt by rails 23 arranged lengthwise on opposite sides of the tracks and the container filling position.

The numeral 38 represents the main driving shaft of the machine which is journaled horizontally and lengthwise in the lower rear part of the main frame.

The parts of each of the filling devices which co-operate directly with each container are constructed as follows:

55 The numeral 64 represents one of a plurality of vertically movable filling heads or nozzles arranged respectively above the several containers while the latter are at the filling stations, each of these heads being provided at its lower end with a downwardly facing rubber or elastic ring 65 adapted to engage the upper edge of one of the containers upon 60 lowering the respective head and form an air tight joint therewith when the head is lowered into its operative position.

65 The several filling heads or nozzles are mounted on a vertically movable yoke 66 which latter is provided with upper and lower flanges 67, 68, in which necks 69 on the upper ends of the heads are capable of sliding vertically. Each of these heads is yieldingly held in its lowermost position on the yoke independently of the other heads by a spring 70 surrounding the respective neck and bearing at its upper end against a collar 71 on the neck, which collar also limits the downward movement of the head by engaging the upper side of the lower yoke flange 68 when the head does not engage a container.

75 The downward movement of the yoke and the parts mounted thereon is effected by gravity but the upward movement of the same is effected by means which comprise a pair of vertically swinging levers 72 pivoted at their inner and outer ends respectively to the main frame and said yoke, a rotary cam 73 secured to a rotary shaft 41, a cam rock arm 74 turning on the shaft 38 and engaging with the cam 73, and a cross bar 75 connecting the rock levers 72 and connected by a rod 76 with the cam rock arm 74.

80 Due to this yielding connection between 95 each filling head and the yoke, each of the heads, upon lowering the yoke, will engage its lower end with the respective container independently of the other heads and thereby enable all of the heads to engage the several 100

containers properly notwithstanding that there may be some variation in the height of the containers or in the thickness of the sealing or packing rings 65 or the position of 5 the heads, inasmuch as the spring 70 of each head will be compressed more or less if the respective head engages its container and is arrested in its downward movement before the yoke completes its downward movement.

10 Each of the filling heads is provided with an inlet passage 77 which extends downwardly therefrom within the neck of the respective container and an outlet passage 78 which opens at the lower end of the head at a point 15 above the lower end of the inlet passage 77. The inlet passage extends to the rear side of the head and is connected by a flexible tube 79 with the lower part of a powder supply bin, hopper or reservoir 80 through the medium 20 of a controlling device. The outlet passage 78 communicates with the neck of the respective head and this neck is connected at its upper end by a flexible tube 81 with a suction manifold 82 mounted on a suitable 25 support such as the front side of the reservoir; as shown in Fig. 1. This suction manifold is connected with an exhaust pump or other suitable exhausting device so that a vacuum is created within the several filling 30 heads and the conduits and containers communicating therewith.

While the filling heads are elevated and not engaged with containers the suction of the pump on the manifold 82 causes the external air to be drawn into the outlet passages of the heads without producing any effect on the powder in the reservoir. When, however, the heads are engaged with the containers, the suction effect of the pump causes 40 air and powder to be drawn from the supply through the supply pipes or tubes 79 and as this powder issues from the lower end of the inlet passage 77 the same is separated from the air due to the reversed direction of 45 movement which the air is compelled to take in escaping through the outlet passage 78, thereby causing the liberated powder to drop into the containers. When a container has been filled with powder up to the lower end 50 of the inlet passage the continued suction of the pump carries the surplus powder thereafter withdrawn from the supply to a separator which may be of any suitable construction, and enables the by-passed powder 55 to be recovered and eventually returned to the reservoir for filling the same into containers.

The material to be packed may be supplied to the reservoir from any suitable source, for 60 example by a pipe, (not shown) leading to the top of the reservoir for replenishing the material when required.

In the absence of any provision to agitate and distribute the material in the reservoir, 65 the same is liable to become packed and flow

unevenly into the several filling heads and to meet this condition an agitating and distributing device is provided consisting preferably of a screw conveyer 85 arranged horizontally and lengthwise in the lower part 70 of the reservoir adjacent to the discharge openings leading to the powder supply tubes.

Between the lower end of the powdered material supply magazine 80 and each supply tube 79 is arranged a controlling device which 75 is preferably constructed so as to also measure the batches of material which are delivered to successive containers. This form of controlling device is best shown in Figs. 1, 2, 3, 4 and 5, and constructed as follows:

The numerals 90, 91, represent the upper and lower sections of a measuring chamber which telescope one within the other so that the capacity of this chamber may be accurately determined by moving these telescopic 85 sections toward and from each other. This adjustment may be effected in any suitable manner but preferably by two right and left hand screws 92 engaging with threaded openings in flanges 93 on opposite sides of the 90 measuring chamber sections, as shown in Figs. 4 and 5, and adapted when turned one direction or another to separate these sections or bring them together for either increasing or decreasing the capacity of the chamber.

The upper section of the measuring chamber is connected by a hollow top 94 with an outlet in the bottom of the material supply reservoir and the lower section of this chamber is connected by a hollow base 95 with the 100 inlet end of the respective supply tube 79. Between the upper measuring chamber section and the top 94 is formed a horizontal guideway 96 in which an inlet slide valve 97 moves for the purpose of bringing a port 98 105 in this valve either into or out of register with the passage leading from the reservoir to the measuring chamber and thus permitting flow of material from the reservoir into the measuring chamber or cutting off such 110 flow. A similar guideway 99 is formed between the lower measuring chamber section and the base 95 in which an outlet slide valve 100 moves for bringing a port 101 in this valve either into or out of register with the 115 passage from the measuring chamber to the respective filling head and thus permit the delivery of the contents of this chamber or shutting the same off. The slide valves are actuated so that they are opened alternately, 120 this being preferably accomplished by a pair of elbow levers 102, 103 mounted on rock shafts 202, 203 journaled in bearings on the main frame and having upwardly projecting arms connected respectively with the upper 125 inlet and lower outlet slide valves while their lower arms project forwardly and backwardly, respectively, from their axes.

The rock shaft 202 carries the several elbow levers 102 associated with the inlet valves 130

of the several measuring chambers and is rocked by means which include a cam 104 on the counter shaft 41, a rock lever 204 which is turned in one direction by said cam 104 and in the opposite direction by a spring 304, and a rod 214 connecting the rock lever 204 with a rock arm 404 on the rock shaft 202.

The rock shaft 203 carries the several elbow levers 103 of the outlet valves of the measuring chambers and is rocked by means which include a cam 303 mounted on the counter shaft 41, a rock lever 503 which is turned in one direction by the cam 303, a spring 603 which turns the rock lever 503 in the opposite direction, and a rod 605 which connects the rock lever 503 with a rock arm 703 on the rock shaft 203, as shown in Fig. 8.

During each cycle of operations of the machine the cams 104, 303, make a complete turn and first cause the upper slide valve 97 to open and the lower slide valve 100 to close so that the measuring chamber will become filled with powdered material, and then cause the upper valve 97 to close and the lower valve 100 to open and permit the suction from the manifold on the filling head to draw the measured quantity of material from the measuring chamber to the container.

In order to prevent the formation of a vacuum in the measuring chamber and to permit the material to be promptly and completely withdrawn therefrom when this chamber is cut off from the supply bin and connected with a filling head, the upper section of the measuring chamber is provided with a plurality of vent openings 107 and also with longitudinal vent grooves 207 in the external flange on the lower part of the upper measuring chamber section, which openings and grooves lead to the outer atmosphere.

Similar vent holes 108 leading from the interior of the measuring chamber to the exterior are provided in the upper part of the hollow base which connects the measuring chamber with the respective delivery tube 79 so as to prevent the formation of a vacuum in this part of the supply passage when the lower valve 100 is closed and thus permits of effectively withdrawing any material therefrom at this time.

The mechanism for operating the slide valves 97, 100, is so timed that the measuring chamber connects with the respective container while its filling head is lowered into engagement therewith, but this chamber is only connected with the supply reservoir while the respective filling head is lifted from its container so that filling of the measuring chamber proceeds while the containers are advanced from one place to another by the conveyer.

If the material to be packed into the containers does not require measuring and the same is of a free flowing character the meas-

uring device may be omitted and instead a single slide valve 109 may be employed in a guideway 110 between the upper and lower sections 111, 112 of a valve casing connecting respectively with the supply reservoir 70 and the delivery tube 79 which valve may be held tightly against the upper section 111 by spring pressed balls 113, as shown in Fig. 6, or otherwise to prevent leakage, and this valve may also be actuated by means which include a rock arm 114 engaging with this valve.

While the containers are located at the filling stations and at points between the same a vibratory or shaking action is imparted to the containers so that the material is settled therein not only while the same is being supplied with material but also while the supplying operation is suspended and the containers are advancing step by step from one filling station to another.

In its preferred form the vibrating or shaking mechanism is constructed as follows:

Arranged underneath the upper stretch of the container feed belt is a vibrating platform consisting preferably of a plurality of longitudinal sections 115 and each mounted on the upper end of a vertical vibrating rod 116 which is guided in a suitable way 117 on the adjacent part of the main frame. Hammer blows in rapid succession are delivered against the lower end of each vibrating rod by a hammer head 120 arranged on the front end of a hammer arm 121 which is mounted at its rear end on a supporting rod 122 carried by the frame. Each of these hammer arms is turned in the direction for engaging its head with the respective vibrating rod by a spring 123 interposed between a tail 124 on the underside of this arm and an abutment on the adjacent part of the frame, as shown in Fig. 1. Projecting upwardly from each hammer arm is a trip finger 224 which is adapted to engage a constantly rotating ratchet wheel 125 on the adjacent part of a rotary shaft 126 journaled lengthwise in suitable bearings on the main frame.

As each ratchet wheel engages its teeth successively with the finger of the companion hammer arm the latter is deflected downwardly and then released so that the resilience of the spring 123 raises the hammer arm and delivers blows in rapid succession and thereby vibrates or shakes the containers so that the material settles therein and thereby permits of more completely and solidly filling the same.

While the containers are in motion and being advanced from one of the stations to another the same are preferably not vibrated and means are therefore provided for this purpose which are constructed as follows:

The numeral 130 represents a supporting rock shaft which is journaled lengthwise and horizontally on the main frame above the

several hammer arms, this shaft being rocked forwardly and backwardly once during each cycle of operations of the machine by an intermediate rock lever 131 turning on the shaft 38 and engaging its lower arm with a cam 132 on the cam shaft 41 while its upper arm is connected by means of a link 133 with an upwardly projecting rock arm 134 on the rock shaft 130, as shown in Fig. 1. The lower arm of the rock lever 131 is held in engagement with the periphery of the cam 132 by means of a spring 135 connecting the upper arm of this lever with a collar on the rock shaft 130.

15 Movably mounted on this rock shaft 130 and depending therefrom is a detent or hold-out pawl or dog 136, which is provided at its upper end with a hub 137 whereby the same is mounted on the shaft 130 while its lower end is adapted to be moved either over a low face 138 or a high face 139 on the upper side of one of the hammer arms 121 which is arranged immediately below the same.

While the containers are at rest at the 25 several filling stations and also at the non-filling zones intermediate of these stations the position of the cam 132 is such that the same operates through the medium of the rock lever 131 and associated parts to turn 30 the rock shaft 130, so that the lower ends of the latter are moved forwardly over the depressed surfaces 138 of the several vibrating hammers, as shown by full lines in Fig. 1. When the parts are in this position each of 35 the hammer arms is free to be thrown by its spring 123 upwardly against the lower end of the respective vibrating rod 116 and also drop with its trip finger 124 from the high to the low parts of the teeth on the periphery 40 of the adjacent ratchet wheel 125, whereby a vibratory or shaking action is imparted to the several containers or cans supported upon the vibrating platforms at the filling stations and intermediate places. As shown 45 in Fig. 1 this vibration is imparted to one of the containers while the upper end of the same is engaged by the respective filling head and powdered material is being delivered from the supply reservoir into this container.

When the filling heads are lifted from the containers the cam 132 turns the rock shaft 130 in the direction for shifting the detent pawls 136 from a position over the depressed 55 faces 138 of the hammer arms, as shown by full lines in Fig. 1 into a position over the elevated faces 139 of these arms, as shown by dotted lines in the same figure, whereby the hammer arms will be held in the depressed 60 position and prevented from striking the lower ends of the vibrating rods, thereby avoiding vibration or shaking of the containers during the time that the filling heads are out of engagement from the same. While 65 the hammer arms are thus depressed the fin-

gers thereof are moved beyond the path of the teeth on the vibrator ratchet wheels so that the latter rotate idly without influencing the position of the hammer arms. When the filling heads are again engaged with the upper or inlet ends of the containers the cam 132 withdraws the several detent pawls 136 from the high faces 139 on the hammer arms so that the latter are again free to be shifted by their springs 123 into a position in which their heads engage with the lower ends of the vibrating rods and the trip fingers thereof move into the path of the teeth of the ratchet wheels so that vibration or shaking of the containers is resumed.

This machine permits of expeditiously filling containers with material which is free-flowing and difficult to control in order to pack the correct amount in each container and it also permits of compacting the material so that the containers need be no larger than necessary, thereby effecting a substantial economy.

I claim as my invention:

A machine for filling containers, comprising a filling head adapted to communicate with the inlet of a container and adapted to be connected with an exhaust device, a material reservoir adapted to supply material to said head for delivery into said container, a conduit for conveying the material from said reservoir to said head, and means for measuring the material passing through said conduit comprising a measuring chamber having an inlet and an outlet, an inlet valve for controlling said inlet, an outlet valve for controlling said outlet, and means for opening and closing said valves alternately, said measuring chamber being provided between said valves with vent openings, and said conduit being provided adjacent to said outlet valve with vent openings.

In testimony whereof I hereby affix my signature.
